UNITED STATES PATENT OFFICE.

JAMES DEGELLEKE, OF SODUS, NEW YORK.

BENCH-VISE.

SPECIFICATION forming part of Letters Patent No. 758,960, dated May 3, 1904.

Application filed June 11, 1903. Serial No. 161,046. (No model.)

To all whom it may concern:

Be it known that I, JAMES DEGELLEKE, a citizen of the United States, residing at Sodus, in the county of Wayne and State of New York, have invented a new and useful Bench-Vise, of which the following is a specification.

The invention relates to improvements in bench-vises.

The object of the present invention is to improve the construction of bench-vises and to provide a simple, inexpensive, and efficient one of great strength and durability adapted to be readily mounted on and removed from a bench or analogous support and capable of firmly gripping a board or plank and of supporting the same in an upright position on one edge while the said board is being planed or otherwise operated on.

With these and other objects in view the invention consists in the construction and novel combination and arrangement of parts hereinafter fully described, illustrated in the accompanying drawings, and pointed out in the claims hereto appended, it being understood that various changes in the form, proportion, size, and minor details of construction within the scope of the claims may be resorted to without departing from the spirit or sacrificing any of the advantages of the invention.

30 In the drawings, Figure 1 is a plan view of a bench-vise constructed in accordance with this invention and illustrating the manner of clamping a board. Fig. 2 is a transverse sectional view on the line 2 2 of Fig. 1. Fig. 3 is a detail perspective view of the cam-lever. Fig. 4 is a detail view of the inner jaw. Fig. 5 is a similar view of the outer jaw. Fig. 6 is a detail view of the pivotal longitudinal bar or lever.

40 Like numerals of reference designate corresponding parts in all the figures of the drawings.

1 designates an inner jaw provided with a straight longitudinal engaging edge or face 2, adapted to fit against a board 3 at the inner side thereof, as clearly shown in Figs. 1 and 2 of the drawings. The inner jaw 1, which is provided with a flat lower face to fit upon a bench or other support, has a depending 45 pin or projection 4, removably fitting in a

perforation of the top 5 of a bench, as clearly shown in Fig. 2. The pin or projection 4, which is formed integral with the jaw, as illustrated in Fig. 2, may be constructed in any other desired manner, as will be readily understood. The inner jaw co-operates with an outer adjustable jaw 6, consisting of a thin longitudinal bar presenting smooth inner and outer faces, the inner face being adapted to engage the outer face of the board 3, whereby the board is firmly clamped in an upright position on one edge. The bar, which constitutes the jaw 6, is provided at one end with a pair of outwardly-extending horizontal ears 7, between which is pivoted one end, 8, of a longitudinal lever 9. The end 8 of the bar or lever 9 is reduced to fit between the ears 7 and is perforated to receive a pivot 10. The other end, 11, of the longitudinal bar or lever 9 is bifurcated to receive a cam-lever 12, and the said bar or lever 9 is provided with a central depending pin or projection 13, preferably formed integral with the bar or lever and adapted to fit removably in a perforation of the bench. One arm of the longitudinal bar or lever is provided with a recessed or cut-away portion 14, located adjacent to the end 8 and adapted to reduce the weight of the bar or lever, which is also provided at its center with an outwardly-projecting lip or flange 15. The lip or flange is adapted to increase the bearing-surface of the longitudinal bench-engaging member or lever at the pivot formed by the depending pin or projection. The cam-lever, which is provided with a circular head, 80 has a slot 16 arranged at an angle to the handle portion 17 of the lever and provided at one side with a series of hook-shaped projections or lugs forming bearings 18 and adapted to receive a pivot 19, which passes through the bifurcated end of the bench-engaging lever or member 9. By this construction the cam-lever is capable of ready adjustment to position the parts of the bench-vise to clamp boards of different thicknesses, and a board 95 or plank may be readily clamped in an upright position on the bench, as indicated in Fig. 2 of the drawings, by simply oscillating the cam-lever. The bench-vise will firmly grip a board or plank and will effectually pre- 100

vent the same from springing out of engagement with it when the board or plank is being planed or otherwise operated on. The cam-lever, which has its head operating in the slot 5 or bifurcation of the longitudinal bar or member 9, projects beyond the bifurcated end of the bar or member and engages the outer face of the adjacent end of the outer jaw. The bar or member 9 is adapted to oscillate on its 10 pivot to permit the adjustable jaw 6 to move inward and outward to accommodate boards and planks of different thicknesses.

The bench - vise, which is preferably constructed of metal, may of course be made of other material, and it is detachably mounted 15 on the bench and is adapted to be readily removed therefrom and replaced thereon, and when detached the jaws are separated from each other. By this construction the bench- 20 vise is handled with the same facility as if it were composed of two sections or members only, as the outer adjustable jaw and the cam-lever are permanently connected with the longitudinal bar or member until the pivots at 25 the ends of the bar or member 9 are removed. These pivots may be constructed in any desired manner, as will be readily understood.

What I claim is—

1. A device of the class described comprising 30 a longitudinal lever fulcrumed between its ends, an adjustable jaw adapted to be secured to a suitable support and connected with one arm of the longitudinal lever, means mounted on the other arm of the longitudinal lever for engaging the adjustable jaw, and a jaw adapted to be secured to a suitable support and coöperating with the adjustable jaw, substantially as described.

2. A device of the class described comprising 40 a lever fulcrumed between its ends, an adjustable jaw adapted to be secured to a suitable support and connected with one arm of the lever, means located at the other arm of the lever for actuating the adjustable jaw, and a jaw 45 adapted to be secured to a suitable support and coöperating with the adjustable jaw, substantially as described.

3. A device of the class described comprising 50 a lever fulcrumed between its ends, an adjustable jaw adapted to be secured to a suitable support and connected with one arm of the lever, a cam-lever located at the other arm of the lever and arranged to actuate the adjustable jaw, and a jaw adapted to be secured to a suitable 55 support and coöperating with the adjustable jaw, substantially as described.

4. In a device of the class described the combination of a lever fulcrumed between its ends,

an adjustable jaw adapted to be secured to a suitable support and connected with one arm 60 of the lever, and means located at the other arm of the lever for actuating the adjustable jaw, substantially as described.

5. In a device of the class described the combination of an adjustable jaw, adapted to be secured to a suitable support and a longitudinal lever fulcrumed between its ends and having one of its ends arranged to actuate the adjustable jaw, and means located at the other arm of the lever for actuating the other end of the 70 adjustable jaw, said means consisting of an adjustable cam - lever, substantially as described.

6. In a device of the class described the combination of an adjustable jaw, adapted to be secured to a support, and a lever disposed longitudinally of the jaw and fulcrumed between its ends, one arm of the lever being pivotally connected with one end of the jaw and the other arm being provided with a pivot, and a 80 cam-lever provided with a slot and having a series of bearings therein to receive the said pivot, said cam-lever being adapted to engage and operate the adjustable jaw, substantially as described.

7. A device of the class described comprising 85 a lever provided between its ends with a depending pivot adapted to engage a suitable support, a jaw connected at one end with one arm of the lever, a cam-lever mounted on the 90 other arm of the lever and engaging the jaw, and a jaw provided with means for detachably engaging a support and adapted to coöperate with the said jaw, substantially as described.

8. In a device of the class described, the combination of the inner jaw having a pin or projection to provide an interlocking connection 95 with a support, the outer jaw adapted to be secured to a suitable support and spaced from the inner jaw, and a lever pivoted to the outer 100 jaw and having a cam bearing upon said outer jaw.

9. In a device of the class described the combination of a lever provided between its ends with a depending pivot adapted to engage a 105 suitable support, a jaw connected at one end with one arm of the lever, and a cam-lever mounted on the other arm of the lever and engaging the jaw.

In testimony that I claim the foregoing as 110 my own I have hereto affixed my signature in the presence of two witnesses.

JAMES DEGELLEKE.
